United States Patent Office.

ALBERT BINGHAM, OF NEWTONVILLE, MASSACHUSETTS.

Letters Patent No. 74,746, dated February 25, 1868; antedated February 7, 1868.

IMPROVEMENT IN KNOB-LATCHES FOR DOORS.

The Schedule referred to in these Letters Patent and making part of the same.

Be it known that I, ALBERT BINGHAM, of Newtonville, in the county of Middlesex, and State of Massachusetts, have invented an Improved Door-Latch, which I term a "Bit-Hole Latch," of which the following is a full, clear, and exact description, reference being had to the accompanying drawing, making a part of this specification, in which—

Figure 1 represents a plan view of the latch within the door.

Figure 2 is a side view of the same; and

Figure 3 is the front end of a door, showing a bit-hole, in which the latch is inserted.

My invention consists in constructing a latch which is actuated by the contraction of a spring, attached at one end to a projection or hook on the face-plate on the edge of the door, and at the other end to an inner part of the latch, the latter being moved by means of a tumbler attached to or placed upon the spindle, to which the handles are secured, and the whole occupying a space which will admit of its being fitted in a bit-hole made through the edge of the door.

Referring to the drawings, A represents a portion of the door, in which the latch is fitted. A hole is made with an auger of the required size in the edge of the door, as indicated at H, fig. 3, into which the latch is inserted. B C is the latch, formed in the shape of an oblong link, as seen on its upper edge in fig. 1, with the catch *b* on its outer end. Its rear end, C, is formed as shown, with a projecting arm, *c*, which overlaps and retains the tumbler D in place, yet admits of its ready removal. The tumbler D consists of a semicircular plate of metal, provided with a square opening, in which is fitted the spindle for the handles, and with two shoulders, so that one of them will press against a portion of the part C of the latch when the latter is to be retracted, which is effected by turning the handle, as usual. The curved end of the opposite side of the disk, when the same is turned to retract the latch, will abut against a cross-piece, *e*, on the latch at its rear, so as to prevent it from turning any further than is necessary to retract the latch sufficiently. To the cross-piece *e* of the latch is attached one end of a coiled spring, S, its other or front end being attached to a projection or hook, *d*, secured to the face-plate on the front edge of the door, through which the catch passes. The said spring serves to keep the latch projected. In fig. 1, the portion colored yellow shows the latch in a retracted position, and that in red in a projected or normal position.

The latch is fixed in the door by first inserting it within the bit-hole H. The tumbler D is then dropped within a hole in the side, when the stem is passed through the door, and fits within a recess in the latch, the latch being first retracted to receive it. The spindle being then passed through the latch and door, the handles are secured as in the usual manner.

The latch, it will be seen, is of very cheap and simple construction, and is very simple and efficient in operation, and not liable to get out of order. It occupies but a small space, and, instead of requiring a mortise, is easily and quickly fitted within a hole made by an ordinary bit.

Having thus described my invention, what I claim as new, and desire to secure by Letters Patent, is—

The combination and arrangement of the latch, having link B and armed end C, the removable tumbler D, and spring S, when the parts are constructed and operating substantially as described.

In testimony whereof, I have signed my name to this specification in the presence of two subscribing witnesses.
